UNITED STATES PATENT OFFICE

RUSSELL RUST HIBBS, OF CAPE GIRARDEAU, MISSOURI

WOOD-GROOVING MACHINE

Application filed December 3, 1929. Serial No. 411,297.

This invention relates to wood grooving machines and more particularly to devices of this character of the portable type.

An important object of the invention is to provide, in a manner as hereinafter set forth, a wood grooving machine of the aforementioned character which includes an electric motor which is mounted thereon in a manner to drive the bit or other cutting tool when the device is in use.

Another important object of the invention is to provide a wood grooving machine of the character set forth wherein means is provided for expeditiously adjusting the cutting bit for regulating the depth of the groove to be cut and wherein the electric motor is associated with the bit supporting means in such a way as to be shifted simultaneously therewith.

Other objects of the invention are to provide a wood grooving machine of the character set forth which will be simple in construction, strong, durable, efficient in its use and which may be manufactured at low cost.

Other objects and advantages of the invention will become apparent from a study of the following specification, taken in connection with the accompanying drawings, wherein like characters of reference designate corresponding parts throughout the several views, and wherein:

Figure 1 is a view in side elevation of a wood grooving machine constructed in accordance with this invention.

Figure 2 is a view in top plan thereof.

Figure 3 is a fragmentary view in longitudinal vertical section showing the bit adjusting and clamping means.

Figure 4 is a detail view in perspective of the bit supporting means and the motor stand.

Figure 5 is a detail view in elevation showing the drive sprocket in which the bit mandrel is mounted.

Figure 6 is a fragmentary detail view in perspective showing the manner in which one of the side walls is recessed to accommodate the bit supporting bracket.

Referring to the drawings in detail, the reference character 1 designates generally the

body portion of the machine which comprises the base 2 and the vertically extending side walls 3 and 4. The side walls 3 and 4 are provided with an intermediate raised portion 5. As it will be seen the body portion 1 constitutes a channel member of substantially U-shaped cross section. As seen most clearly in Figure 3 of the drawings, the sides 3 and 4 of the body portion are provided with rearwardly and upwardly extending recesses 6 and a portion of the base 2 is directed upwardly as at 7, and terminates at the upper end of the recesses 6 to provide an opening in said base 2.

A pair of inclined ribs 8 are oppositely disposed on the inner side of the walls 3 and 4 and extend upwardly and rearwardly thereon from the peripheral edges of the recesses 6. A motor stand 9 (see Figure 4) is mounted in an inclined position between the side walls 3 and 4 through the medium of the channel 10 in its longitudinal side edges which slidably receive the ribs 8 for adjustably supporting said stand between said side walls.

On one side, the motor stand 9 is provided with a laterally projecting bracket 11 which extends below the lower end of the motor stand and is bifurcated to provide a pair of journal arms 12 for rotatably supporting the opposite end portions of a bushing 13. A sprocket 14 is rigidly mounted on the bushing 13 at a point between the journal arms 12 as clearly shown in Figure 4. The bushing 13 is provided with a longitudinal bore 15 for the reception of a disc supporting mandrel 16 having a left hand screw threaded portion 17 on its free end. The mandrel 16 is provided with an integral flange or collar 18 for abutment with the adjacent end of the bushing 13 which collar acts as a stop to limit the movement of said mandrel through the bushing. On the opposite end of the bracket 11 a retaining nut 19 is threaded on the projecting end of the mandrel 16 for rigidly mounting the same in the bushing.

A set screw 20 is threaded through the bushing 13 adjacent the sprocket 14 for engagement with the adjacent portion of the mandrel 16 for further rigidly coupling said mandrel and bushing together. An integral lon-

itudinally extending key or rib 21 is provided on the mandrel 16 for securing a grooving bit or other woodwork bit thereon in a manner to prevent relative rotary movement 5 of said bit with respect to the mandrel and this key may extend into a complementary opening in the bushing 13 if it is desired to provide the same. The key receiving channel in the bushing 13 is designated by the reference character 22. If desired, the key 21 10 may be dispensed with and the mandrel 16 provided with a flat side and the bore 15 of the bushing 13 may also be provided with a flat side to conform to the cross sectional 15 shape of the mandrel for rigidly securing said mandrel therein against rotation. A bit 23 is rigidly mounted on the mandrel 16 against rotation thereon and a nut is mounted on the threaded portion 17 for retaining 20 the bit thereon.

It is understood, of course, that the bit 23 is provided with a bore having a groove in one side for the reception of the key 21 or if the mandrel 16 is provided with a flat side, the 25 bore in the bit will be provided with a complementary flat side for keying the bit thereto.

The wall 4 is provided with a recess or slot 24 which merges into the recess 6 (see Figure 6) for accommodating the bracket 11. The 30 mandrel 16 with the bit 23 mounted thereon is disposed in the recess provided in the body portion 1 by the recesses 6 and the upturned portion 7 of the base 2.

An electric motor 25 is mounted on the upper end of the stand 9 through the medium of 35 the supporting plate or arm 26 and the securing screws 27 which extend therethrough and are threaded in the openings 28 in the upper end portion of said stand. The armature 40 shaft 29 of the motor extends laterally therefrom and has mounted on its free end a sprocket 30. An endless driving chain 31 is trained over the sprocket 30 and the sprocket 14 on the bushing 13.

The underside of the motor stand 9 is provided with a centrally disposed longitudinally extending dovetail groove 32 for slidably receiving a complementary block 33 having a rearwardly extending arm 34 thereon 50 provided with a transverse opening for rotatably receiving a horizontally disposed shaft 35 which has its opposite end portion journaled in the bushings 36—36 in the side walls 3 and 4. At a point adjacent the inner faces 55 of the side walls 3 and 4 the shaft 35 has rigidly mounted thereon a pair of pinion gears 38—37' which mesh with a pair of rack bars 37 formed integrally with the lower side of the motor stand 9 and at the opposite side 60 portion thereof. A set screw 38 is threaded into the rear end of the arm 34 for engagement with the shaft 35 for securing the same against rotation when desired and said set screw is provided with a hand wheel or disc 65 39 at its free end.

A bridge piece 40 spans the side walls 3 and 4 and is secured thereto through the down turned end flanges 41 for the passage of securing elements such as rivets 42. The bridge piece 40 is provided with a down turned forward portion 43 on which is formed an integral internally threaded sleeve 44 for threadedly receiving a pressure screw 45 provided, at its upper end, with a hand wheel 46. A pressure plate 47 is engaged on the lower 70 end portion of the motor stand 9 and has its opposite end provided with recesses for the reception of the guide ribs 48 for adjustably mounting said pressure plate on the side walls 3 and 4. The pressure plate 47 has rigidly mounted on its upper side a comparatively small plate 49 which is provided with a longitudinal groove 50 in its upper face for the reception of the adjacent end of the pressure screw 45.

A laterally adjustable longitudinally extending gage 51 is mounted on the body portion 1 of the machine through the medium of the rods 52—52 which extend through transverse bores provided in the sleeve 53—53 formed on the base 2 and extending between the side walls 3 and 4. Set screws 54—54 are threaded into the sleeves 53 for engagement with the rods 52 for maintaining the gauge in adjusted position. The gauge 51 is provided with a recess 55 for accommodating the bracket 11 when said gauge is moved close to the side wall 4.

An upstanding handle 56 is mounted centrally between the side walls 3 and 4 on the base 2 adjacent the rear ends thereof and is provided, on its upper end, with a suitable electric switch 57 for controlling the flow of electric current to the motor 25 through the conductor wires 58. It is understood, of course, that the wires 58 lead to a suitable source of current supply. Adjacent the forward end of the base 2 a hand knob 59 is rigidly mounted on said base. The reference character 60—60 denotes a pair of oil cups mounted on the bracket 11 for lubricating the bushing 13 at its opposite end portion.

The gauge 51 is the thickness of the wall 4 and is of greater width at its bottom to allow the same to come flush with the inside of the body portion when making narrow cuts. The recess 55 in the gauge 51 must be large enough to allow the chain and sprocket to operate without touching said gauge when the same is set for wide cuts.

In the use of the machine, with the parts assembled as shown in the drawings, the pressure screw 45 is backed off to relieve the pressure of the plate 47 on the motor stand 9 and the set screw 38 is also disengaged from the shaft 35 after which the said shaft 35 may be rotated through the medium of the hand wheel which is designated by the reference character 35' and which is mounted on the projecting end of the shaft which ex- 120 125 130

tends through the side wall 3 as clearly seen in Figure 2. Rotation of the shaft 35 shifts the motor stand 9 in an inclined plane on the ribs 8 through the medium of the rack bars 37 and the pinion gears 37' which are rigidly mounted on the shaft. In this manner the bit 23 is set at a point to make the desired depth of cut after which the set screw 38 is again tightened on the shaft 35 and the pressure screw 45 is screwed downwardly to engage the pressure plate 47 tightly against the motor stand 9, and all of the elements which relate to the cutting mechanism are thus clamped firmly in adjusted position. The set screw 38 prevents rotation of the shaft 35 and the pressure plate 47 in conjunction with the pressure screw 45 maintains the motor stand 9 against vibration as well as any other undesired movement. It will further be seen that the motor 25 will be moved simultaneously with the bit 23 by reason of the fact that it is mounted rigidly on the stand 9 and, of course, sufficient slack is provided in the electric conductor which extends from said motor to the switch 57 to permit this adjustment to be made without breaking or straining said conductor.

Any suitable type of bit may be mounted on the mandrel 16 and the tool may be utilized to plane doors of any thickness as well as for making moldings such as screen mould and window stops or for rabbeting door jambs.

It is believed that the many advantages of a wood grooving machine constructed in accordance with this invention will be readily understood, and although the preferred embodiment of the invention is as illustrated and described, it is to be understood that changes in the details of construction may be had which will fall within the scope of the invention as claimed.

What is claimed is:—

1. A wood grooving machine of the character described comprising a body portion having a base and opposed side walls, an inclined stand adjustably mounted for sliding movement between the side walls, a bit rotatably supported on the lower end of the stand, a motor mounted on the stand, means driven by said motor to rotate the bit and means for shifting the stand on the body portion comprising rack bars formed integrally on the base and pinion gears in operative engagement with the rack bars and rotatably supported between the side walls.

2. A wood grooving machine of the character described comprising a body portion of substantially U-shaped cross section and including a base and vertical opposed side walls having horizontally aligned recesses in their lower portions, said base being provided with an opening communicating with the recesses in the side walls, an inclined stand adjustably mounted on the side walls,

a bracket projecting laterally and downwardly from said stand adjacent the outer face of one of the side walls and terminating in horizontal alignment with the recesses therein, a mandrel journaled in said bracket and extending into the recesses, a bit rigidly mounted on the mandrel, a motor on the upper end of the stand, means driven by said motor for rotating the bit and means mounted on the side walls for adjusting the stand in an inclined plane.

3. A wood grooving machine of the character described comprising a body portion of substantially U-shaped cross section and including a base and vertical opposed side walls having horizontally aligned recesses in their lower portions, said base being provided with an opening communicating with the recesses in the side walls, an inclined stand adjustably mounted on the side walls, a bracket projecting laterally and downwardly from said stand adjacent the outer face of one of the side walls and terminating in horizontal alignment with the recesses therein, a mandrel journaled in said bracket and extending into the recesses, a bit rigidly mounted on the mandrel, a motor on the upper end of the stand, means driven by said motor for rotating the bit and means mounted on the side walls for adjusting the stand in an inclined plane, said means comprising a shaft journaled for rotation, at its opposite end portion, in the side walls, pinion gears rigidly mounted on said shaft for rotation therewith, rack bars mounted on the adjacent side of the stand in mesh with the pinion gears, said stand being further provided, on its lower side, with a longitudinally extending dovetail groove, a complementary block slidably disposed in the groove and having a rearwardly extending arm provided with an opening for rotatably receiving the rotating shaft and manually operable means for rotating the shaft.

4. A wood grooving machine of the character described comprising a body portion of substantially U-shaped cross section and including a base and vertical opposed side walls having horizontally aligned recesses in their lower portions, said base being provided with an opening communicating with the recesses in the side walls, an inclined stand adjustably mounted on the side walls, a bracket projecting laterally and downwardly from said stand adjacent the outer face of one of the side walls and terminating in horizontal alignment with the recesses therein, a mandrel journaled in said bracket and extending into the recesses, a bit rigidly mounted on the mandrel, a motor on the upper end of the stand, means driven by said motor for rotating the bit and means mounted on the side walls for adjusting the stand in an inclined plane, said means comprising a shaft journaled for rotation, at its opposite end portion,

tion, in the side walls, pinion gears rigidly mounted on said shaft for rotation therewith, rack bars mounted on the adjacent side of the stand in mesh with the pinion gears, 5 said stand being further provided, on its lower side, with a longitudinally extending dovetail groove, a complementary block slidably disposed in the groove and having a rearwardly extending arm provided with an opening for rotatably receiving the rotating 10 shaft and manually operable means for rotating the shaft, means mounted on the block engageable with the shaft for retaining the same against rotation, a pressure plate supported for movement in an inclined plane on 15 the side walls on the opposite side of the stand, and a pressure screw supported on the body portion for clamping the pressure plate against the stand.

20 In testimony whereof I affix my signature.
RUSSELL RUST HIBBS.
